(57) **CLAIM**

The ornamental design for a dispenser holder with decorative plate, as shown and described.

DESCRIPTION

FIG. 1 is an isometric view of a top, front, and right side of an ornamental design for a dispenser holder with decorative plate;

FIG. 2 is a front elevational view of the holder and plate of FIG. 1;

FIG. 3 is a rear elevational view of the holder and plate of FIG. 1;

FIG. 4 is a right side elevational view of the holder and plate of FIG. 1, the left side elevational view being a mirror image thereof;

FIG. 5 is a top plan view of the holder and plate of FIG. 1; FIG. 6 is a bottom plan view of the holder and plate of FIG. 1; FIG. 7 is an isometric view of a top, back, and left side of the holder and plate of FIG. 1;

FIG. 8 is an isometric view of a different embodiment of the holder and plate shown in FIG. 1; and,

FIG. 9 is a front elevational view of another ornamental design of the dispenser holder with decorative plate shown in FIGS. 1-8.

The dashed lines representing the decorative image provided on a surface of, or within, the plate of the embodiment of FIG. 9 represents some type of decorative image, which is not positively claimed in the embodiment. The remainder of the broken lines in the drawings depict environmental subject matter only and form no part of the claimed design.
